(57) **CLAIM**

I claim the ornamental design for adhesive tape having non-linear side edges, as shown and described.

DESCRIPTION

FIG. 1 is a front, top and side perspective view of the adhesive tape having non-linear side edges.

FIG. 2 is a top plan view thereof, the bottom being identical to the top shown in FIG. 2.

FIG. 3 is a side edge elevational view thereof.

FIG. 4 is a side edge elevational view thereof; and,

FIG. 5 is an end edge elevational view thereof, the end edge opposite to the end shown in FIG. 5 being identical.
